UNITED STATES PATENT OFFICE

JOSEPH E. HOLVECK, OF PITTSBURGH, PENNSYLVANIA, ASSIGNOR TO THE ALDRICH
PUMP COMPANY, A CORPORATION OF PENNSYLVANIA

PUMP

Application filed May 17, 1929. Serial No. 363,891.

This invention relates to pumps and more particularly to a compensating device for eliminating the surge or pressure variations in the discharge of pumps such, for example, as hydraulic pumps.

An object of this invention is to provide a device for use with reciprocating pumps constructed and arranged so as to eliminate the surge or variations in pressure always present in discharge lines of such pumps.

A further object is to provide a compensating device of the type set forth which can be readily applied to pumps already in operation.

15 A further object is to provide a compensating device of the type set forth which will be simple and rugged in construction, efficient in operation and easy to manufacture and install.

20 These and other objects which will be apparent to those skilled in this art, are accomplished by means of the invention illustrated in the accompanying drawing, in which Figure 1 is a side elevation of a reciprocating pump provided with one embodiment of this invention. Figure 2 is a similar view taken from the right of Figure 1. Figure 3 is a partial sectional view through a compensating device constructed in accordance with one 25 embodiment of this invention.

The particular embodiment of this invention which has been chosen for the purposes of illustration is shown in connection with a triplex reciprocating pump of standard 30 form. The invention includes a separate compensator cylinder which is open to the discharge line of the pump. A plunger is associated with this compensator cylinder and is operated in such a manner that when the 35 discharge flow of the pump is above the desired mean, the plunger will move outwardly so as to permit the compensator cylinder to absorb the excess water or other material from the discharge line of the pump. On 40 the other hand, when the pump discharge is less than the mean, the plunger will be moved into the cylinder and force the surplus water back into the discharge line at a rate which will bring the discharge flow up to the desired 45 means.

In the illustrated embodiment the compensator plunger is operated by means of a cam which is secured directly to the crank shaft of the pump, the layout of the cam being determined from ordinary well known engineering principles and being such as to give the desired movement to the compensator plunger.

As illustrated, the compensator includes a cylinder casing 10 and a plunger 11 operative therein, and controlled by means of a roller 60 and cam mechanism 27 and 28, respectively. The cylinder casing 10 is provided with a port 14 connected by a pipe 14' to the discharge line 15 of a multi-cylinder pump 30. The plunger 11 has an extending rod 13 which projects through the cylinder casing 10. To prevent loss of liquid and pressure around the rod 13 and plunger 11 in the cylinder casing 10, the latter is provided with packings 16 and 17, respectively, held in position by glands 18 and 19, respectively.

The plunger 11 has a yoke 21 rigidly secured at the outer end for supporting a roller 27 on a small axle 22. This roller 27 is adapted in any suitable manner for rotation in respect to its yoke 21, and for engagement with a suitably designed cam 28.

This cam 28 is adapted to be secured to and rotatable with the crank shaft 44 of a suitable multi-cylinder pump 30.

The extending rod 13 of the plunger 11 is provided with an encircling spring 24 which is held in place between the gland 18 and a washer 25 by a lock nut 26 threaded on the end of this rod 13. This spring is of sufficient strength to reduce the thrust of the roller 27 against the cam 28. In other words, of sufficient strength so that the encircling spring 24 will resist the pressure in the cylinder chamber 12 just enough to permit sufficient force on the plunger 11 to keep the roller 27 against the cam 28 and to cushion the piston against pressure of liquid in the cylinder. Thus, the piston 11 is sensitive to the pressure in the discharge line, thereby lessening the operating burden of the cam 28.

The cylinder casing or wall 10, as seen from Figure 3, has an inner and centralizing disposed cylinder or chamber 12, whose diameter

is larger than the diameter of the plunger 11 operative therein. It will be noted that the plunger 11, having an upper piston portion terminating in a lower rod portion, is completely encircled by the wall 10 through the opposite ends of which it extends. Further, the opposite ends of the casing 10 have inwardly extending slots of a diameter somewhat greater than the diameter of the plunger portion received therein, which near the outer edges are threaded to receive glands 18 and 19. These glands 18 and 19 are employed to hold suitable packing, 16 and 17, respectively, within the enlarged slotted portions. The upper or piston portion of the plunger member 11 in normal position is disposed somewhat above the central portion of the inner cylinder or chamber 12. This is accomplished by positioning a spiral spring 24 over the extending rod portion 13 of the member 11 and holding it in place between the lower gland 18 and a nut and washer means 25-26 positioned at the extreme end of the rod 13. Thus, it will be seen that, apart from the central chamber 12, the device has no air chamber, but completely encircles the plunger 11 to prevent any air whatsoever getting into the fluid chamber 12 and thus "upsetting" the charted discharge rate.

The device is adapted for use with any multi-cylinder pump 30 such as shown in Fig. 2; the particular pump illustrated being of a vertical triplex single acting type; but, it will be apparent that this invention can be readily adapted to any single or double acting type of multi-cylinder pump.

As shown, the pump 30 is operated by means of any suitable source of power 29 provided with a shaft 31 and a coupling 33. This coupling drives the shaft 32 and is positioned between the frame 35 of the pump and an auxiliary supporting structure 36. A gear 34 is rigidly secured to this shaft 32 for rotation therewith. This gear 34 meshes with a gear 35 which drives the crank shaft 44 of the pump. The plungers of this pump are indicated as 37, 38 and 39 in the drawing and the suction line as 40 and the discharge line as 15.

In practice, the design of the circumference of the cam 28 is in conformity with the curve of the combined discharge of the cylinders of the pump at any given interval and for a complete revolution of the crank shaft. Point 50 of this cam 22 represents a point on the curve of the discharge of the pump when it is below mean, and 51 a point when the discharge is above mean.

In general, the cam 28 is so timed that when the discharge of the pump is above mean or at a point such as 51, the differential plunger will have moved out in its compensating cylinder 12, taking the excess discharge fluid into the cylinder, but when the discharge is less than mean, such as at a point 50, the differen-

tial plunger 11 will have moved into the cylinder 12 and forced out into the discharge line of the pump 30 sufficient liquid to bring the discharge thereof up to the mean desired.

In employing this invention the port 14 is connected with the discharge line 15 of such a pump as 30, as the cylinder 10 is rigidly secured at a suitable position on the frame 35 and cam 28 is rigidly secured to the end of the crank shaft 44 for rotation therewith in timed relation thereto.

What I claim as new and desire to secure by Letters Patent is:

1. The combination with a discharge apparatus having a crank shaft and a discharge line, of means secured to said apparatus and cooperating therewith for maintaining a constant rate of flow in said discharge line, said means including a cylinder casing having a chamber in open communication with said line, a plunger associated with said chamber and having a piston portion terminating at one end in a rod portion, said portions extending through opposite ends of said casing, a resilient means positioned on the extending rod portion of said plunger for holding said plunger in a normal position, a plunger-operating-cam secured to said crank shaft for moving said plunger, so that said plunger will be operated to force more liquid into the discharge line when the discharge of the apparatus is below mean.

2. The combination with a discharge apparatus having a crank shaft and a discharge line, of means secured to said apparatus and cooperating therewith for maintaining a constant rate of flow in said discharge line, said means including a cylinder casing in open communication with said line, a plunger associated with said cylinder and having a piston portion terminating at one end in a rod portion, said portions extending through opposite ends of said casing, the extending portions of said plunger being sealed at entry into said cylinder casing, so that said chamber will be air-proof, a resilient means disposed on the extending rod portion of said plunger for holding said plunger in a normal position, and a plunger-operating-cam secured to said crank shaft for moving said plunger, so that said plunger will be operated to force more liquid into the discharge line when the discharge from the apparatus is below mean.

3. The combination with a discharge apparatus having a crank shaft and a discharge line, of means secured to said apparatus and cooperating therewith for maintaining a constant rate of flow in said discharge line, said means including a cylinder casing in open communication with said line, a plunger associated with said cylinder and having a piston portion terminating at one end in a rod portion, said portions extending through opposite ends of said casing, said piston portion

having a diameter less than the diameter of said chamber, the extending portions of said plunger being sealed at entry into said casing so that said chamber will be air-proof, a resilient means disposed on the extending rod portion of said plunger for holding said plunger in a normal position, a plunger-operating-cam secured to said crank shaft for moving said plunger, so that said plunger will be operated to force more liquid into the discharge line when the discharge from the apparatus is below mean.

4. The combination with a discharge apparatus having a crank shaft and a discharge line, of means secured to said apparatus and cooperating therewith for maintaining a constant rate of flow in said discharge line, said means including a cylinder casing having an inner chamber in open communication with said line, a plunger associated with said chamber and having a piston portion terminating at one end in a rod portion, said portions extending through opposite ends of said casing, the extending portions of said plunger being sealed by gland and packing means from entry into said casing until entry into said chamber so that said chamber will be air-proof, a resilient means positioned on said extending rod between the end thereof and the face of the casing, so that said plunger will maintain a given position with respect to said chamber, a plunger-operating-cam secured to said crank shaft for moving said plunger, said cam having a circumferential outline conforming to the curve of the combined discharge of the units of said discharge apparatus, so that said plunger will be operated to force more liquid into the discharge line when the discharge from the apparatus is below mean.

5. The combination with a discharge apparatus having a crank shaft and a discharge line, of means secured to said apparatus and cooperating therewith for maintaining a constant rate of flow in said discharge line, said means including a cylinder casing having an inner chamber in open communication with said line, a plunger associated with said chamber and having a piston portion at one end terminating in a lower rod portion, said portions extending through opposite ends of said casing, said piston portion having a diameter smaller than the diameter of said chamber, the extending portions of said plunger being sealed by gland and packing means from entry into said casing until entry into said chamber, so that said chamber will be air-proof, a spring positioned on said extending rod between the end thereof and the lower face of the casing, so that said plunger will maintain a given position with respect to said chamber, a plunger-operating-cam secured to said crank shaft for moving said plunger, said cam having a circumferential

outline conforming to the curve of the combined discharge of the units of said discharge apparatus, so that said plunger will be operated to force more liquid into the discharge line when the discharge apparatus is below mean. 70

6. The combination with a discharge apparatus having a crankshaft and a discharge line, of means detachably secured to said apparatus and cooperating therewith for maintaining a constant rate of flow in said discharge line, said means including a cylinder casing having an inner chamber in open communication with said line, a plunger associated with said chamber and having an upper piston portion terminating in a lower rod portion, said portions extending through opposite ends of said casing, said piston portion having a diameter less than the diameter of said chamber, the extending portions of said plunger being sealed by gland and packing means from entry into said casing until entry into said chamber, so that said chamber will be air-proof, a spring positioned on said extending rod between the end thereof and the lower face of the casing, so that said plunger will maintain a given position with respect to said chamber, a plunger-operating-cam detachably secured to said crankshaft for moving said plunger, said cam having a circumferential outline conforming to the curve of the combined discharge of the units of said discharge apparatus, so that said plunger will be operated to force more liquid into the discharge line when the discharge from the apparatus is below mean. 80 85 90 95 100

7. The combination with a discharge apparatus having a crankshaft and a discharge line, of means detachably secured to said apparatus and cooperating therewith for maintaining a constant rate of flow in said discharge line, said means including a cylinder casing having a centrally disposed chamber in open communication with said line, a plunger having an upper piston portion terminating in a lower rod portion, said plunger being disposed for operation in said chamber and being positioned to extend through opposite ends of said cylinder casing, the upper of said piston portions having a diameter smaller than the diameter of the chamber in which it is disposed for operation, the portions of said plunger extending through the opposite ends of said casing being tightly sealed and being positioned to slide therethrough, a resilient means positioned on the extending rod portion of said plunger and abutting against the lower face of said casing for holding said plunger in a normal position, a plunger-operating cam detachably secured to said crankshaft for moving said plunger, said cam having a circumferential outline conforming to the curve of the combined discharge of the units of said discharge 110 115 120 125 130

apparatus, so that said plunger will be operated to force more liquid into the discharge line when the discharge from the apparatus is below mean.

5 In testimony whereof, I have hereunto subscribed my name this 11th day of May, 1929.

JOSEPH E. HOLVECK.
